ROBERT H. PRATT, OF NEW YORK, N. Y.

DESIGN FOR WALL-PAPER.

Design No. 17,674, dated August 30, 1887.

UNITED STATES PATENT OFFICE.

ROBERT H. PRATT, OF NEW YORK, N. Y.

DESIGN FOR WALL-PAPER.

SPECIFICATION forming part of Design No. 17,674, dated August 30, 1887.

Application filed July 5, 1887. Serial No. 243,480. Term of patent 3½ years.

To all whom it may concern:

Be it known that I, ROBERT H. PRATT, a citizen of the United States, residing at New York, in the county of New York and State of New York, have invented a certain new and original Design for Wall-Paper; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

15 The invention relates to a certain new and original design for wall-papers, and is conventional in style, and will be hereinafter more particularly described and claimed, reference being had to the accompanying drawings, forming a part hereof, and in which is illustrated the invention.

The design is made up of figures like daisies, their leaves and stems arranged in flowing scrolls.

20 To more particularly describe the design,

there is illustrated a series of flowing scrolls, A, as shown, formed in imitation of stems B and leaves C of the daisy flower, and having thereon the figures D of daisies. The stems and leaves may be of a dull-brown or golden 30 color, while the flowers may be in bronze, gold, and silver colors.

The design has been described with considerable particularity, but only for fullness and clearness, without so far limiting the design as 35 not to cover substantially the same and colorable imitations thereof.

Having described the invention, what I claim is—

The design for wall-paper, consisting of flowing scrolls, as shown, representing the stems and leaves of the daisy flower and daisy figures on said stems, substantially as shown and described.

In testimony whereof I affix my signature in 45 presence of two witnesses.

ROBERT H. PRATT.

Witnesses:

THEODORE CHATTERTON,
GEO. HAMANN, JR.
